(57) **CLAIM**

I claim the ornamental design for a carriage part for a standing umbrella, as shown and described.

DESCRIPTION

FIG. 1 is side elevation view of a standing umbrella and showing my new design;

FIG. 2 is a perspective view of my design shown in FIG. 1; FIG. 3 is a rear elevation view of my design shown in FIG. 1; FIG. 4 is a front elevation view of my design shown in Fig. 1; FIG. 5 is a left side elevation view of my design shown in FIG. 1;

FIG. 6 is a right side elevation view of my design shown in FIG. 1;

FIG. 7 is a top view of my design shown in FIG. 1; and, FIG. 8 is a bottom view of my design shown in FIG. 1. The broken lines are shown to illustrate environmental structure and form no part of the claimed design.

The article in which the design is embodied is a carriage part used for moving a boom of a standing umbrella along the umbrella upright support rod.
